[57] CLAIM

The ornamental design for a compound bow with a cable tension adjustment, substantially as shown and described.

DESCRIPTION

FIG. 1 is a front elevation of a compound bow with cable tension adjustment according to the invention.

FIG. 2 is a view of the left side thereof.

FIG. 3 is a view of the right side thereof.

FIG. 4 is a rear view thereof.

FIG. 5 is a top view thereof.

FIG. 6 is a bottom view thereof.

FIG. 7 is a view of the right side of an alternate embodiment for use by a left handed person in which the view is a mirror image of the view of FIG. 2. The left side image being likewise a mirror image of the view of FIG. 3 and the rear view being substantially identical with that of FIG. 4.

FIG. 8 is a front view of the alternate embodiment of FIG. 7.
